WIRING TECHNIQUES FOR CORES

James C. Hathaway, Corona del Mar, Calif., assignor to
Collins Radio Company, Cedar Rapids, Iowa, a cor-
poration of Iowa

Filed Apr. 16, 1962, Ser. No. 187,546
1 Claim. (Cl. 29—241)

This invention relates in general to wiring jigs, and in particular to a jig for facilitating the wiring of a plurality of magnetic cores, such as used in magnetic core logic circuits. As is well known to those skilled in the art, magnetic cores may be used as logic elements for digital applications, such as the control or arithmetic sections of computers. Magnetic core circuits include many cores mounted in matrices to provide complex logic functions.

It is an object of the present invention to provide a jig for wiring such cores in a simple manner which eliminates the tediousness of picking up each individual core and inserting the wire and aligning the cores.

A feature of this invention is found in the provision for a jig with individual arms for holding magnetic cores and in which the arms may be individually adjusted so as to selectively position the cores in a manner to facilitate winding the cores.

Further advantages, features, and objects of the invention will become apparent from the following description and claim when read in view of the drawings, in which:

FIGURE 1 is a perspective view of the winding jig of this invention; and,

FIGURE 2 is a plan view showing a different arrangement of the arms of the jig than shown in FIGURE 1.

With reference to FIGURE 1 a main body member 10 has an upwardly-extending portion 11 which is suitably secured to the body portion by holding screws 12. Body portion 10 is formed with a plurality of spaced slots 13 through which arms 14 extends. The adjusting ends 16 of arms 14 are provided with notches 17 to move the arms relative to the body portion within the slots 13.

A second raised portion 18 is formed at the opposite side of the body portion and has guide slots 19 into which cores 21 formed with central openings 22 may be received. The arms 14 have core-holding portions 23 adjacent their ends which are adapted for receiving and clamping there-

2

in the magnetic cores 21. Portions 23 comprise spring clamps into which the cores may be inserted.

Thus the structure of FIGURE 1 comprises a jig for holding a plurality of magnetic cores, and by selectively moving the arms 14 relative to the holding jig different cores may be aligned with each other to facilitate simple and rapid winding. For example, the arrangement shown in FIGURE 1 comprises a winding wherein alternate cores are commonly wound so that a needle 24 with wire 26 attached through a suitable eye can be threaded through alternate cores as desired.

Likewise, the second group of cores which are further removed from the edge 27 of the body member than the other cores are aligned and may be wound with the needle 24.

It is seen that any pattern desired may be established by moving the arms 14 transversely of the body member in the slots 19 and 13, and winding may be accomplished rapidly either manually or by machine.

It is seen that this invention provides a jig for winding cores, and although it has been described with respect to a preferred embodiment thereof, it is not to be so limited, as changes and modifications may be made therein which are within the full intended scope of the invention as defined by the appended claim.

I claim:

A winding jig comprising a body portion formed with a pair of upwardly-extending portions, a plurality of core supporting arms extending through the first of said upwardly-extending portions and slidably movable relative thereto, slots formed through the first upwardly extending portion and receiving the arms therethrough for such slideable movement, a plurality of grooves formed in the other upwardly-extending portion, core engaging means at the end of each arm adapted to receive cores therein slidably engaging its associated groove whereby the cores may be moved relative to the grooves formed in the second upwardly-extending portion.
